UNITED STATES PATENT OFFICE.

GEORGE R. LOCKWOOD, OF ST. LOUIS, MISSOURI.

COMBINED LETTER SHEET AND ENVELOPE.

SPECIFICATION forming part of Letters Patent No. 279,405, dated June 12, 1883.

Application filed July 31, 1882. (No model.)

To all whom it may concern:

Be it known that I, GEORGE R. LOCKWOOD, of the city of St. Louis, Missouri, have made a new and useful Improvement in a Combined Letter Sheet and Envelope, of which the following is a full, clear, and exact description, reference being had to the annexed drawings, making part of this specification, in which—

Figure 1 is a view of the sheet developed, 10 the upper right-hand corner of the sheet being turned over to show the mode of applying the gum; and Fig. 2, a view of the sheet as when folded and sealed.

The same letters denote the same parts.

15 In the present improvement there are obtained, in combination, these advantages: The sheet can be readily sealed and as perfectly as in a sealed envelope, and the construction is such as to offer no obstacle to the taking of a 20 letter-press copy.

A represents a sheet of writing-paper. It may be note or letter size, and is preferably ruled, as now indicated in the drawings. At one corner—say the upper left-hand corner—the 25 sheet is provided with the flaps a and a' . These flaps extend from the corner a^2 along the edges a^3 a^4 , respectively, and as far as is needed to inclose the sheet when folded, and as herein-after explained. These flaps are not gummed, 30 nor does any adhesive substance appear upon the face of the sheet; but upon the back of the sheet, at one of the corners, a^5 a^6 —say the corner a^5 —and in extent and direction to correspond to, and, when the sheet is folded and 35 the flaps turned over thereupon, to come beneath, the flaps, an adhesive substance, a^7 a^8 , is applied. The sheet is inclosed by folding it so as to bring that part of the back of the sheet 40 to which the gum a^7 a^8 is applied opposite the flaps a a' —that is, the edge having the gum a^7 comes opposite the flap a , and the edge having the gum a^8 opposite the flap a' . The gummed portions a^7 a^8 are then moistened and the flaps turned down thereupon and secured 45 thereto, as seen in Fig. 2. The lines of folding the sheet are indicated by the broken lines B C , the sheet being folded on the horizontal line B and then on the vertical line C . In case the gum is applied at the corner a^6 , instead of

at the corner a^5 , the sheet would be folded first 50 on the line C and then on the line B . A further modification is folding the sheet horizontally or vertically, or both horizontally and vertically, more than once. For instance, the sheet may be folded on a horizontal line, B' , 55 and a second time on the horizontal line B'' , and then, after having been folded horizontally it may be folded once or more times vertically. When thus folded more than once, either horizontally or vertically, the flaps a a' 60 are extended on the edges a^3 a^4 only to opposite the lines B'' C' , respectively, as indicated by the dotted lines b'' c' , respectively.

The lines of the folds above referred to may be indicated on the face or inner side of the 65 sheet by ruling or by dotted lines, or in any desired way.

The sheet may be perforated at D D' to facilitate the opening of the sheet after having 70 been sealed.

It will be noticed that when the sheet has been folded and sealed, as described, the inner side or face of the sheet is entirely inclosed, the flaps serving to seal the only edges of the sheet which after the folding remain open 75 or detached. The construction, when brought into the shape shown in Fig. 2, therefore is as effectually closed as if in an envelope. From putting the gum upon the back a^6 of the sheet this benefit accrues: The moistened sheet of the 80 letter-copy book can be freely pressed against the face of the sheet A without adhering thereto, which difficulty is experienced when any adhesive substance is upon the face of the sheet or its flaps.

70
85
I claim—

1. The sheet A , having flaps a a' and lines of perforation a^3 a^4 , and a gummed edge, a^7 a^8 , on the back, substantially as described.
2. The sheet A , ruled on its face, marked at 90 C and B , or C' C'' and B'' , having flaps a a' , and a gummed edge, a^7 a^8 , on its back, substantially as described.

GEORGE R. LOCKWOOD.
